United States Patent

Des. 237,667
Patented Nov. 18, 1975

237,667

YARN HOLDER

Alvan M. Percelay, Pawtucket, R.I., assignor to Craft Yarns of Rhode Island, Inc.

Filed Sept. 24, 1973, Ser. No. 400,417

Term of patent 14 years

Int. Cl. D15—06

U.S. Cl. D3—19 A

FIG. 1

FIG. 2

FIG. 3

FIG. 4

FIG. 5

FIG. 6

FIG. 1 is a perspective view of a yarn holder showing my new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is an end view thereof.

I claim:

The ornamental design for a yarn holder, substantially as shown.
